CLAIM

The ornamental design for a combined rechargeable flashlight and recharging stand therefor, as shown and described.

DESCRIPTION

FIG. 1 is a perspective view of a combined rechargeable flashlight and recharging stand therefor showing my new design;

FIGS. 2-7 are, respectively, rear, top, bottom, left side, right side and front views of the rechargeable flashlight, the recharging stand being omitted for purposes of disclosure;

FIGS. 8, 9, 10, 11 and 12 are, respectively, rear, top, left side, right side and front views of the combined rechargeable flashlight and recharging stand as shown in FIG. 1; and

FIG. 13 is a perspective view of the recharging stand, the rechargeable flashlight being omitted for purposes of disclosure.
